UNITED STATES PATENT OFFICE.

EMIL KROHN, OF DULUTH, MINNESOTA, ASSIGNOR OF ONE-THIRD TO AXEL W. BJORK-LUND, OF MINNEAPOLIS, MINNESOTA, AND ONE-THIRD TO VICTOR LILLQUIST, OF DULUTH, MINNESOTA.

DOOR-OPERATING MECHANISM.

Application filed October 4, 1926. Serial No. 139,340.

This invention relates to a door operating mechanism particularly adapted for opening doors of garages or other buildings in which automobiles are kept. It is desirable to have some means for opening the garage doors from the outside thereof and it is very desirable to be able to open the doors without getting out of the automobile. While it has heretofore been proposed to provide a door operating mechanism with means for operating the same actuated by the driven wheels of an automobile, such mechanisms have employed flexible members extending to the doors and the door opening means. Such flexible members have proved impractical and such devices have been practically inoperative and not commercially successful. It is an object of this invention, therefore, to provide means for opening and closing the doors of a garage or other building which an automobile enters, which may be operated without the necessity of the driver getting out of the automobile.

It is a further object of the invention to provide means for opening and closing the doors of a garage or other building which an automobile enters, which means are operated by the driven wheels of the automobile, a set of said means being provided at the outer side and the inner side of said doors and being connected by a rigid member.

It is more specifically an object of this invention to provide a door operating mechanism comprising a pair of rollers disposed outside of the door, a pair of rollers disposed inside of the door, said pairs of rollers being adapted to support and be driven by the driven wheels of an automobile, said rollers having shafts carrying gears, and a member geared to said shafts and operatively connected to the doors to open and close the same.

These and other objects and advantages of the invention will be fully set forth in the following description made in connection with the accompanying drawings, in which like reference characters refer to similar parts throughout the several views and in which:—

Fig. 1 is a plan view of the door operating mechanism, the walls of a garage or building and the doors thereof being shown in horizontal section, certain parts being indi-

cated in different positions in dotted lines; 55

Fig. 2 is a central vertical section of Fig. 1, taken on line 2—2 thereof, shown on an enlarged scale, and certain portions being broken away;

Fig. 3 is a plan view of a modified form of 60 door operating mechanism, the doors being shown in horizontal section;

Fig. 4 is a vertical section taken on line 4—4 of Fig. 3, as indicated by the arrows:

Fig. 5 is a vertical section taken on line 5—5 of Fig. 3, as indicated by the arrows;

Fig. 6 is a plan view of another modified form of door opening mechanism, a portion of a building and the doors being shown in horizontal section and certain parts being indicated in different positions in dotted lines; 70

Fig. 7 is a vertical section taken on line 7—7 of Fig. 6; and

Fig. 8 is a vertical section taken on line 8—8 of Fig. 6.

Referring to the drawings, particularly Figs. 1 and 2, a garage or other building in which an automobile is kept or enters is shown having the side walls 10 and the end walls 11. A pair of doors 12 are shown 80 swinging outward to open position about the vertical axes of the hinges 13. The doors 12 have L-shaped brackets 14 secured thereto adjacent their lower ends and disposed somewhat toward the hinges 13. The brackets 14 have pivoted thereto the ends of links 15 which converge away from the doors and have their upper ends pivoted by a common pivot 16 to a guide member 17. The member 17 has a portion projecting into and guided in a slot 18^a extending longitudinally of a plate or casting 18 which will be secured or set into the floor of the building, as shown in Fig. 2. A pair of bearing boxes 19 are set into the floor of the building, 90 having parallel sides forming bearings for a pair of parallel shafts 20, which shafts have secured thereto within the boxes 19 rollers 21. As shown in Fig. 1, there is a pair of rollers spaced a short distance from each other in each of the boxes 19. The rollers 21 project slightly above the floor of the building, as shown in Fig. 2. The shafts 20 extend between the boxes 19 in a pit 22 formed in the floor of the building, and 100 have secured thereto between said boxes 19 pinions 23. The pinions 23 mesh with a rack bar 24 disposed below the same and

105

which is connected at its inner end to the guide member 17. The guide member 17 may have one or more rollers 25 journaled therein adjacent its bottom, which travel 5 on the bottom of the pit 26 formed beneath the plate 18. The rack bar 24 is connected at its rear end or extended to form a rod 24^a extending through the pit 26 and through a pipe or conduit 27 embedded in the material of the driveway approaching the building. Said rod 24^a is connected to or formed at its other end as a rack bar 28. The rack bar 28 has disposed beneath the same and meshes with, a pair of pinions 29 and said 10 rack bar at one end moves in contact with the under surface of a plate 30 disposed over and forming a cover for a pit 31 in which said rack and pinions 29 are disposed. The pinions 29 are carried respectively on shafts 32 which extend through the sides of bearing boxes 33 disposed at the ends of lateral portion 31^a of the pit 30. The shafts 32 have secured at each end thereof rollers 34 disposed in the boxes 33, which 15 rollers are similar to the rollers 21 already described and extend a short distance above the top of the plate 30. The rollers 34 are disposed some distance in front of the doors 12.

30 In operation when the doors 12 are closed and the automobile is to enter the building, the same will be driven so that the rear or the driven wheels thereof will be supported upon the rollers 34. These rollers rotate 35 quite easily and the same will be rotated by the rear wheels of the vehicle when the same are driven, each wheel being in the position and rotating as shown at 35 in Fig. 2. The pinions 29 will be rotated as indicated by the arrows in Fig. 2 and rack bar 28 will be moved away from the doors 12. This moves rod 24^a and rack bar 24 so that the pinions 23 are rotated in a direction opposite to the dotted lines shown in Fig. 2. 40 The guide members 17 will thus be moved to the right as shown in Fig. 2 and its other end will travel in the guide slot 18^a of plate 18. The links 15 will be moved outwardly and will swing the doors 12 open, the doors and links moving to the positions shown in dotted lines in Fig. 1. When the guide member 17 reaches the end of the guide slot 18^a it will be stopped and the racks 24 and 28 can then move no farther. The rollers 34 45 will thus be held from rotation by gears 29 and shafts 32 and the automobile may advance off of the rollers and move into the building. When the automobile moves into the garage or building, the rear wheels will move onto the rollers 21. These rollers will then be rotated by the wheel 35, the wheel occupying the position and rotating as shown in the dotted lines in Fig. 2. The pinions 23 will be rotated as indicated by the arrows in 50 Fig. 2 and the rack 24 will be moved in-

ward, thus again moving the rack 28 inward. The movement of the rack 24 will also move member 17 to the inward end of slot 18^a which will form a stop and prevent further movement of members 17 and 24. 70 The doors 12 will thus be closed. When it is desired to run the automobile out of the garage or building, the wheels thereof will be reversely driven to the direction indicated in dotted lines in Fig. 2 and the rack 24 will be moved outward, thus moving the member 17 to the outer end of slot 18^a. When the member 17 reaches the outer end of said slot, the wheels 21 cannot be further rotated and the automobile will move off 80 of the rollers 21 out through the doors 12 and brought into position with the rear or driven wheels over and supported on the rollers 34. These rollers can then be rotated in the direction opposite to that indicated 85 in Fig. 2 and the rack bar 28 will be moved toward doors 12 and the doors closed by the movement of rack 24, member 17 and links 15. The members 17 will move to the inner 90 end of slot 18^a and the automobile can then back off of the rollers 34 leaving the doors 12 in closed position. The doors 12 are thus moved to open and closed position merely by the movement of the automobile wheels and it is unnecessary for the driver of the 95 automobile to leave his seat therein.

In Figs. 3, 4, and 5 a modified form of the device is shown. In this form the rollers 34 and 21 are provided as before, which will be mounted in the driveway and the floor of the building as shown in Figs. 1 and 2. The rollers 34 will be connected as described by the shafts 32, which are in turn connected by a chain 32^a running over sprockets secured thereto. The rollers 21 will be connected by the shafts 20 which are also connected by chains 20^a running over sprockets secured thereto. One of the shafts 32 has a beveled gear 36 secured thereto meshing with a beveled gear 37 carried on the end of shaft 38, which extends longitudinally of the driveway and building and which will be disposed below the surface of the driveway and floor. The shaft 38 has a beveled gear 39 secured at its other end, meshing with a beveled gear 40 secured to one of the shafts 20. The shaft 38 also has secured thereto a worm gear 41 meshing with the worm wheel gear 42 secured to a transverse shaft 43 which will be journaled in suitable bearings 44 secured in a pit 47 formed in the floor of the building. The shaft 43, however, extends with its axis substantially aligned with the axes of the doors 12 and said shaft has secured to its ends 110 beveled gears 45 meshing with gear segments 46 secured to the bottoms of the doors 12 and rotating about the axes of the pintles 48 of the door hinges 49. The doors 12 will be provided with suitable stops 50. 115 120 125 130

In operation the rollers 34 will be disposed in front of the doors 12 as shown in Fig. 1 and will be rotated by the driven wheels of the automobile as already described. This will rotate the shaft 32 and the beveled gears 36 and 37 so that shaft 38 will be rotated. The worm gear 41 will thus be rotated, rotating worm wheel gear 32 and shaft 43 so that the segments 46 will be rotated by gears 45 and the doors 12 swung to open position against stops 50. When the doors engage said stops, the gears and rollers 34 cannot be further rotated, so that the automobile can move off of the rollers 15 into the building. The automobile will be moved to position with its driven wheels resting on the rollers 21 which will be rotated and the shaft 38 will then be rotated in a reverse direction through the gears 40 and 39. This will rotate shaft 43 in the reverse direction and the doors will be moved to closed position. When the doors are in closed position, they will engage stops (not shown) and if desired, the automobile can 25 move off of the rollers 21. It is not necessary, however, that the automobile wheels move off of the rollers 21 and they preferably will remain on said rollers until it is desired to again open said doors 12 to take 30 the automobile out of the building. The driven wheels of the automobile will be moved in the reverse direction and will rotate the rollers 21, thus rotating shafts 38 and 43 and the segments 46 in a direction 35 to open the doors. After the automobile has passed through the doors it may be brought onto the rollers 34 and the driven wheels may be rotated in a reverse direction to rotate shafts 38 and 43 so that the doors will 40 again be closed. It will be seen that the doors can be opened and closed without the necessity of the driver leaving the automobile.

In Figs. 6 to 8, a structure is shown by means of which the driver can open the doors by hand without leaving the automobile. A pair of standards 51 are provided and secured in the concrete or other material of the driveway as shown in Fig. 8, 50 which standards will have bearings 51^a at their upper portions which may be formed of standard tees. The shaft 52 is journaled in the bearings 51^a having a hand wheel 53 at one end thereof which wheel will be disposed at a height for the driver of the automobile to operate the same while he is still in the automobile. The shaft 52 carries a pinion 54 at one end adapted to mesh with a beveled gear segment 55 secured to one of 55 the doors 12, and rotating about the axis 56 of the hinged pintle of the door. The doors 12 will have links 57 pivoted to brackets 58 secured thereon, which links 57 converge inwardly and are pivoted by the pivot 57^a to 60 a guide bar 59 which is movable in spaced

members or castings 60 secured to the floor or ceiling of the building. The castings 60 have guide rollers 61 journaled therein engaging the sides of the bar 59 and said bar carries stop members 59^a adapted to engage 70 the adjacent sides of members 60 when the doors are in closed or wide open position.

In operation the automobile will be positioned in front of the doors 12 and the driver will turn the wheel 53, thus turning 75 the segment 55 and opening one of the doors 12. This door will pull upon its link 57 and the guide bar 59 will thus be moved longitudinally and through the other link 57 will open the other door 12. The doors may be so closed by reverse movement of the hand wheel 53.

From the above description it is seen that applicant has provided a simple, practicable and efficient mechanism for conveniently 85 opening and closing the doors of the garage or other building which an automobile is adapted to enter.

The device comprising rigid members, there is no chance for lost motion to occur 90 and no chance for the members to lengthen in use. The doors will thus always be brought to proper open and closed position. The parts of the device are few and the same are easily made and assembled. 95

The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the 105 novel parts and combinations of parts disclosed and defined in the appended claims.

What is claimed is:—

1. The combination with a door swinging about a vertical axis, of a rigid member connected to the door and adapted to be moved to open and close said door, a second rigid reciprocating member connected to said member for moving the same, two pairs of rollers disposed respectively at the inner 115 and outer sides of said doors, the rollers of each pair being side by side, and adapted to be operated by the driven wheels of an automobile and a rigid member extending between said rollers and geared to one of said 120 rollers of each pair and extending to and connected to said second mentioned member for operating the same and opening and closing said doors.

2. An operating mechanism for opening 125 and closing doors hinged about vertical axes having in combination, a set of spaced pairs of axially aligned rollers adapted to support and be driven by the driven wheels of an automobile, a pair of swinging doors 130

at one side of said set of rollers, a second set of similar rollers at the other side of said doors, a rigid reciprocating member extending between and geared to one of said rollers 5 of each set and movable thereby, and rigid relatively movable means connected to said doors and pivotally connected to said member for opening and closing said doors.

3. A door operating mechanism having in combination, a set of spaced pairs of rollers, the rollers in each pair being side by side and the rollers of the respective pairs being axially alined, said pairs being adapted to support and be driven respectively by the driven wheels of an automobile, shafts connecting said axially alined rollers, pinions carried by said shafts, a rack at one side of said pinions meshing therewith, a swinging door at one side of said rollers, a second 10 set of similar rollers at the other side of said door, shafts connecting the axially alined rollers of said second set, pinions carried by said last mentioned shafts, a rack at one side of said latter pinions and meshing therewith, said racks being connected, a member moving at right angles to said doors when in closed position, connected to said racks, and means connected to said member and said doors for opening and 15 closing said door.

4. A door operating mechanism having in combination, spaced pairs of rollers, the rollers in each pair being side by side and the rollers of the respective pairs being axially alined, shafts connecting said axially alined rollers, gears on one of said shafts, a pair of swinging doors at one side of said rollers, another pair of similar rollers at the other side of said doors, shafts connecting 20 said latter rollers, gears carried on one of said latter shafts, a member extending between said first mentioned and last mentioned shafts and operatively connected to

said gears, swinging means connected to said doors and rigid members connecting 45 said last mentioned member and said means.

5. A door operating mechanism having in combination, spaced pairs of rollers, the rollers in each pair being side by side and the rollers of the respective pairs being 50 axially alined, shafts connecting said axially alined rollers, gears on said shafts, a pair of swinging doors at one side of said rollers, another pair of similar rollers at the other side of said doors, shafts connecting 55 said latter rollers, gears carried on one of said shafts, a member extending between said first mentioned and last mentioned shafts and operatively connected to said gears, a guide member connected to said last mentioned member, means for limiting the movement of said guide member, and means connected to said doors and said guide member for opening and closing said doors upon 60 movement of said guide member.

6. A door operating mechanism having in combination, spaced pairs of rollers, the rollers in each pair being side by side and the rollers of the respective pairs being 65 axially alined, shafts connecting said axially alined rollers, gears on one of said shafts, a pair of swinging doors at one side of said rollers, another pair of similar rollers at the other side of said doors, shafts connecting 70 said latter rollers, gears carried on one of said latter shafts, a member extending between said first mentioned and last mentioned shafts having gear teeth at each end disposed at opposite sides respectively of said member and meshing with said first 75 and second mentioned gears respectively, and links pivotally connected to one end of said members and to said doors.

In testimony whereof I affix my signature.

EMIL KROHN.
